UNITED STATES PATENT OFFICE.

JASPER CALVIN BROWN, OF LOS ANGELES, CALIFORNIA.

CURTAIN.

1,407,248.

Specification of Letters Patent. Patented Feb. 21, 1922.

Application filed November 26, 1920. Serial No. 426,642.

To all whom it may concern:

Be it known that I, JASPER CALVIN BROWN, a citizen of the United States, residing at Los Angeles, (post-office address 1867 Winfield Street,) in the county of Los Angeles and State of California, have invented new and useful Improvements in Curtains, of which the following is a specification.

This invention relates to shades, curtains, and the like. The invention has particular reference to any curtain or shade which is adapted to be drawn upwardly or to one side by means of strings, ropes and other mechanism. The invention is particularly adaptable for use with the commercially known Austrian and French shades.

The invention has for an object the provision of means for raising a curtain so that the same is gathered at a determined zone other than at the bottom of the curtain, then maintaining the gathered portion at said zone in progressive diminishment during the lowering of the curtain.

In practicing the invention, assuming that either an Austrian or French shade is being used, I provide means associated with said curtain which means in turn is associated with the means used for operating (raising or lowering) the shade or curtain. Said first named means preferably includes some friction member through which the second named means may pass and be frictionally engaged thereby. Said second-named means may comprise continuous strings or cord members. Ordinarily Austrian shades are arranged so that they have parallel up and down shirred portions extending across the same. Between each shirred portion are ring members placed equidistant longitudinally from each other. Transversely extending across said shade and near the bottom portion thereof, or just before the scalloped portion thereof, is placed a heavy rod, usually formed of cast iron. This rod functions as a means for maintaining the curtain in a taut position. The opposite end of said curtain or shade is usually tacked to the upper part of the window casing, and ring members are likewise fastened to said casing. Cord members are passed through the ring members attached to the casing and one separate unit of said cord members passes down through the rings attached to the curtain and finally is attached, in each case, to the cast iron rod. All of the cords are brought out at one side of the window cas-

ing and extend downwardly so that when a person draws upon the cords the shade is drawn upwardly. A hook of some form is screwed into or otherwise held to a side of the window casing, so that the corded elements may be wrapped around the same to maintain the shade at any desired height. It is obvious that as the shade is drawn upwardly, it begins to be gathered and become full at the lower portion thereof. This causes a break in its uniform appearance, causing a thick part to appear at the bottom, while the upper extremities of the shade are as even as they were before. This uneven appearance is not pleasing to the eye, and in order to overcome this fault I have provided means which will cause the gathered fullness to occur at the top of the shade instead of the bottom. Ordinarily, the top of the shade is covered by a lambrequin, said lambrequin tending to give the shade a finished appearance. By utilizing the method about to be described, the gathered fullness in the curtain will occur under the lambrequin and be maintained there whether the curtain is drawn upwardly or lowered or in the case of casement window shades, drawn to one side or returned to the original position. Hence the curtain below the lambrequin hangs normally, not losing any of its pleasing appearance.

The method to be described is applicable to any style of shade, other than the roller shade.

The invention has for further objects the provision of an improved device to be used in connection with improved means and method of raising and lowering curtains, which will be superior in point of relative simplicity and inexpensiveness, taken in conjunction with utility, durability, and general efficiency and serviceability.

With the above mentioned and other objects in view, the invention consists in the novel and useful provision, formation, construction, combination, association and interrelation of parts, members and features, as illustrated in some of its embodiments in the accompanying drawings, described in the following detailed statement, and finally pointed out with particularity in the claims.

In the drawings:

Figure 1 illustrates an Austrian type of shade which incorporates the improved means for raising or lowering said shade, the said shade being gathered at its top por-

tion with the lambrequin partly broken away to show said gathering.

Figure 2 is a fragmentary perspective view of a shade and the improved means in connection therewith;

Figure 3 is a view similar to Figure 2 and showing the effect of using the improved means, said curtain acquiring its fullness at the top instead of the bottom;

10 Figure 4 is a fragmentary perspective view of a shade utilizing the improved means and shows the result of lowering the curtain from the position shown in Figure 3;

Figure 5 is a fragmentary elevation of a certain element used in practicing the invention;

Figure 6 is a view similar to Figure 5 with the said element revolved ninety degrees in the plane of the Figure;

20 Figure 7 is an element used in the device illustrated in Figures 5 and 6;

Figure 7^a is a further view of said element;

Figure 8 is a fragmentary elevation of a pulley means used in practicing the invention;

Figure 9 is a plan view of a friction means used in co-operation with the curtain and the cord elements in practicing the invention;

Figure 9^a is a plan view showing the friction element of Figure 9 in a folded position;

Figure 9^b is a front view of the means shown in Figure 9^a;

Figure 9^c is a cross-sectional side elevation of the means shown in Figure 9^a and Figure 9^b;

Figure 10 is a modified plan view of a friction element;

Figure 10^a is a plan view of the friction element shown in Figure 10 with the same in folded position;

Figure 10^b is a cross-sectional side view of the device shown in Figure 10^a;

Figure 11 is an elevation of an Austrian shade utilizing the improved means for raising the same;

Figure 12 is a fragmentary elevation showing a modification of the improved means for raising and lowering a shade;

Figure 13 is an elevation of a certain element used in practicing the invention;

Figure 14 is a diagrammatic view illustrating the manner of raising the shade, utilizing the improved means;

Figure 15 is a fragmentary perspective view, certain parts being sectioned, of means utilized for holding the curtain in position, as well as being used for enclosing the improved means for raising or lowering said curtain;

60 Figure 16 is a fragmentary elevation of a member which may be used in practicing the invention; and

Figure 17 is a fragmentary median sectional view of the member shown in Figure 16.

Corresponding parts in all the figures are designated by like reference characters.

Referring with particularity to the drawings, A designates a shade and B designates in its entirety the improved means for said shade.

As pointed out, the shade A may be of any form, either the well known Austrian shade or French shade or any shade adapted to be moved by means of cords.

Referring to Figures 1, 2, 3, 4, 11 and 12, it will be observed that the shade A in said figure is of the commercially known Austrian style. Said shade has between its intermediate shirred portions a braid 8, extending longitudinally thereon. One end of

75 said shade, as at 9, may be tacked to a retaining medium or structure 10, which usually consists of a board adapted to be fastened to the upper part or side of the window casing, as shown at 11. The opposite end of said curtain A carries a rod 12 ranging transversely across the same, as shown at 13. This rod is usually placed just

80 above the scalloped portions 14, where scalloped portions are used. Friction members a or b are sewed or otherwise mounted upon or attached to the braid 8, and in spaced relation to each other, as shown. A continuous cord 40 is carried over the sheave

85 elements c attached to an under side of the retaining medium 10 as shown. From thence said continuous cord 40 passes downwardly and has one of its lengths as 57 confined by the elements a or b with the lower bight 90

of the cord 40 in connection with the rod 12, while the upper bight passes over a sheave member d. A further cord 59 connects with the sheave member d, and the cord 59 continues over to a side of the window casing

95 95 and then extends downwardly so that the same may be grasped. A plurality of said cords 40 are provided, one for each braid or each part which extends between the shirred portions of the shade. Thus it will

100 appear that the cords 40, where they are, in co-operation with the shades, each arranged parallel with one another. Upon pulling said cords 40 through the medium

105 of the cord 59, the curtain or shade A will assume an appearance similar to that shown in Figures 1 and 3, that is to say, the fullness due to the gathering of said shade will

110 be at the top thereof as shown, at 64. A releasing of the cord 59 will allow the curtain to be lowered as shown in Figure 4,

115 with the fullness due to the gathering maintained at all times at the top of the curtain though in progressive diminishment.

Particularizing the improved means B for the shade may include in one of its embodiments a friction means a or b, which

120 friction means may consist of a blank cut in the form shown either in Figure 9 or Figure 10. Obviously, other types of fric-

125 130

tion means might be utilized, but the devices herein depicted are sufficient for our purpose. The friction means *a* is so formed that it has two outstanding lugs or ears 15 and 16, adapted to be bent upwardly at the dotted line 17, 18, 19 and 20. The ears 15 and 16 are likewise bent at the portions shown as dotted at 21 and 22 in an outward direction. It is to be noted that the friction means *a* is provided with a perforation 23 and that the friction means *a* likewise has small perforations 24 located therein. When the friction means *a* is properly bent on the dotted lines, it will assume an appearance similar to that shown in Figures 9^a, 9^b and 9^c. In said Figures it is to be observed that the perforations 24 now register with each other, that is to say, the perforation 24 shown in the ear 15 will register with the perforation 24 shown as at 25, and the perforation 24 in the ear 16 will register with the perforation 24 shown at 26. A tongue member 27 is bent downwardly as shown at 28, so that it may engage a surface of the friction means *a* as shown at 29. The friction means *b* shown in Figure 10 likewise has outstanding ears 30 and 31, provided with perforations 32 therein. The friction means *b* has a perforation 33 located at a median portion of said means as at 34. The friction means *b* is adapted to be bent at the dotted portion illustrated at 35 and 36 and when so bent will assume the appearance shown in Figures 10^a and 10^b. Said friction means *b* likewise has pressed therein two tongue members 37 and 38 adapted to co-operate with each other. One of said friction members, either *a* or *b*, is sewed to the curtain on the tape portion 1 thereof, or if the curtain does not have a tape portion, at the point where the tape is normally placed, said friction means *a* or *b* being sewed to the curtain A through the eyes or perforations 24 of the friction means *a*, or eyes 32 of the friction means *b*. In the sewing thereof it makes little difference whether the friction means *a* has the perforated portion 23 extending directly upwardly or directly downwardly. However, one of said positions must be assumed; the friction means cannot have the perforation 23 or 33 transverse the tape 1.

Upon the rod 12 is mounted a small pulley or ring 39. A continuous or non-ending cord 40 termed the operating means passes downwardly through the perforation 23 of the friction means *a*, or the perforation 33 of the friction means *b*, and is engaged by the tongue member 27 or the tongue members 37 and 38, depending upon which friction means is used. Said cord likewise passes through the ring or pulley member 39, and then back up without engaging the curtain at all. The continuous cords engage means *c*, which means is joined with the retaining me-

dium 3. Said means *c* is in the form of a double sheave and is illustrated in Figures 5 and 6. Said means *c* has a yoke member 41 which encases two sheaves 42 and 43. Said yoke member 41 may have a retaining medium as 44, consisting of a screw joined with the same, so that the means *c* may be joined with the retaining medium 10 as shown at 45. The sheave 42 is roughened as shown at 46 on its periphery and each of said sheaves 75 is carried on axles or pins 47 and 48, passing through the bore in said sheaves and through perforations in the side walls of the yoke 41 of the means *c*. It is to be noted from Figure 5 that the sheave 42 is in advance of the 80 sheave 43. In other words, that they are in a staggered relation to each other.

The sheave 42 is made in such a manner that it may turn in one direction only. Any small clutch element might be incorporated. 85 However, in Figures 7 and 7^a I have shown a means for accomplishing the desired result and which means shows that a portion surrounding the bore 49 of said sheave 42 is offset and arcuated as shown at 50. Within 90 said offset portion may be placed a small roller member 51. Obviously, when the sheave 42 is within the yoke 41 of the means *c*, the roller member 51 cannot escape from the offset portion 50. The sheave 42 may 95 rotate in the direction indicated by the arrow at the top of said sheave 42 in Figure 7, because the roller member 51 will engage an abrupt wall portion 52 of said offset portion 50. However, if it were attempted to rotate 100 the sheave 42 in the direction indicated by the appended arrow in Figure 7^a, the roller would engage a restricted arcuated portion as shown at 53 of the offset portion 50, and prevent said rotation. The lower roller member 43 is allowed to rotate in either direction. 105

In Figure 8 is depicted the ordinary type of sheave designated in its entirety by *d*, in which a sheave member 54 is mounted for rotation in a yoke member 55 provided with 110 a ring member 56.

Referring again to Figure 2, the continuous cord member 40 termed the operating means is brought upwardly so that one of its lengths as 57 termed the rising length, is 115 brought over the sheave 42 and the free length as 58, which is not attached to any friction means, is brought over the sheave 43. The sheave *d* also engages the bight of the continuous cord 40 and acts as one means for 120 divisioning the lengths 57 and 58 of the continuous cord. Attached to the ring member 56 may be a cord 59. Now, assuming that a plurality of shirred portions on the curtain A are provided as shown in Figure 11, 125 and that a plurality of the means *c* are attached to the retaining medium 3 as shown in Figure 11 at 60, 61, 62 and 63, likewise a plurality of continuous cord members 40 arranged as just stated and passing through 130

friction means and connected with ring or pulley members 39, attached to the rod 12, as well as a plurality of cords 59 joined with rings 56 on sheaves *d*, let us see what happens upon pulling the cord or cords 59.

Referring to Figure 3, which illustrates one portion of the shade A, it will be observed that when the cords 59 are pulled, the curtain becomes full at a zone adjacent its line of attachment with the supporting member 10.

The portion 57 of the cord 40 was moved twice around the sheave 42, in order to cover the roughened surface 46 thereof and to prevent slippage. When the cord 59 in Fig. 2 was pulled in the direction indicated by the arrow, the sheaves 42 and 43 both rotated together and the lengths 57 and 58 both moved upwardly an equal distance, each rotating over their respective sheaves. In this upward movement, the friction means *a* or *b*, depending on which is used, tended to grip the length 57 of the cord 40 and carry the curtain upwardly.

Obviously, the friction means would not have to carry the weight of the rod 12, as the weight of the rod 12 was being carried by the cord 40; the friction means really carries the weight of the curtain itself.

However, this weight is distributed between all the friction means and would therefore practically be negligible. Naturally, the first friction means *a* or *b* located near the top of the curtain as at 65, would be the

first means to be affected by a movement of the cord 40. Said friction means would tend to move upwardly and try to follow the length 57 of the cord 40, in its movement over the sheave 42. However, this

is prevented by placing a thin strip of wood or other material 66 under the retaining medium 10 as shown at 67 to keep the curtain A flat adjacent said friction means as shown at 65. Thus, as the lengths 57 and

58 of the continuous cord 40 start their movement, the friction means shown at 65 with the curtain A will engage the strip 66 and prevent its further movement. When this occurs, the cord will be drawn through

said friction means and the next friction means as shown at 68 will move upwardly, carrying with it its portion of the shade and hit the upper friction means as shown at 65, being prevented from further movement upwardly by said friction means, and so on, throughout the length of the shade.

It might appear that if the friction means gripped the cord 40 too tightly, that the opposite end of the shade would tend to curl inwardly and be carried upwardly. However, a moment's thought immediately demonstrates that the weight of the rod 12 would prevent this from occurring.

It will now be seen why the sheaves 42 and 43 are staggered, one reason being so that

the two lengths 57 and 58 making up the continuous cord 40, will be separated from one another. It will also be seen why the sheave 42 is made so as to turn only in one direction. If the sheave 42 were allowed to rotate in both directions similar to the sheave 43 upon releasing the cord 56 so that it would travel in the direction indicated by the arrow in Figure 4, the curtain A, instead of coming down evenly, would allow the entire puffed portion or gathered fullness 64 to come down en masse. However, as the length 57 of the cord 40 is moved around the pulley 42, and as the pulley 42 can only move in one direction, that portion as 57 of the cord 40 cannot move, and hence when the cord 56 is released so that it may move in the direction of the arrow as indicated in Figure 4, the length 58 termed the lower- 85 length will commence its movement and allow the rod 12 to carry or rather pull the curtain A back into position. In so doing, the curtain gradually pulls each friction means down the cord length 57 and 90 allows the curtain to come back down evenly, with the gathered fullness 64 at all times maintained in progressive diminishment at the top of the curtain as shown.

It is obvious that a method has been described whereby a curtain or shade may be raised or lowered or moved to one side, as in the case of casement shades, by allowing the fullness to be acquired at any zone desired. In Figure 11, the plurality 100 of cords 59 may be brought out at an end, as at 69. However, we immediately run into difficulties; in the first place, the nearer the means *c* approaches the point 69, the less chance has the continuous cord 40 to move. 105 In Figures 2, 3 and 4, if the curtain was four feet in length, the pulley *d* would have to be moved approximately four feet in order to completely gather the curtain, hence if the curtain had three Shirred portions as shown in Figure 11, each of the pulleys *d* would have to be moved approximately four feet, and this would be an impossibility in the construction shown in Figure 11. Hence, the continuous cords 115 40 may be lengthened so as to pass over sheaves within a medium *e* shown in Figure 13. Said medium comprises a yoke 70, provided with partitions 71, and likewise with a plurality of upper and 120 lower sheave members 72 and 73 confined between said partitions. Said yoke likewise has a medium as 74, attached to the same, as at 75, so that said yoke member may be joined with the retaining medium 125 10 as at 76, see Fig. 12. As stated, each continuous cord member 40 has its length 57 brought over one of the sheaves 72 and the other length 58 of each of the cord members 40 brought over one each of the 130

sheaves 73. Thence the lengths 57 and 58 pass downwardly within a means *f* illustrated in Figures 16 and 17. Thus it will be seen that the respective continuous cord members 40 are of varying lengths.

The means *f* may include an ornamental tassel provided with a head portion 77. Said head portion includes a cap member 78, having a threaded engagement with a portion as 79. The interior of said head 77 is hollow. The portion 78 is provided with an axle or pin 80, upon which are rotatably mounted sheaves 81. Each sheave is spaced from the other by means of partitions 82, within said cap 78. Likewise the cap is provided with a series of spaced perforations 83. It is intended that the lengths as 57 and 58, after they have been brought over the sheaves 72 and 73 in the means *e*, should pass downwardly through the perforations 83 and over the sheaves 81 within the cap 78, as illustrated in Figure 16 and Figure 17. Thus, as the means *f* is pulled downwardly, the curtain A will be raised as shown in Figure 3.

The means just described may be considered cumbersome and it may be desired to so arrange the curtain and the means associated therewith, that it will not be necessary to pull upon a means *f* the distance required to raise the curtain. To accomplish a new result, an arrangement similar to that shown in Figures 14 and 15 may be utilized. In Figure 14, which may represent the curtain shown in Figure 11, it is noted that a different method is presented for raising the curtain. In Figure 14 the different points of the curtain will be designated as 83, 84, 85 and 86. At each of said points the friction means *c* is used. The chief difference between the different points lies in the number of sheaves used. It is simply making use of the mechanical advantage methods of arranging sheaves. In Figure 5 only one sheave, *d*, is used, while in Figure 14 three sheaves are used instead of one. That is to say, the means *d* has two sheaves, as 87 and 88, and a third sheave, 89, provided with a yoke, is attached near the means *c* shown at 83 to the retaining means or structure 10. The length 57 is brought up over the sheave 42, thence over the sheave 87, back over the sheave 89, down over the sheave 88 to where it joins what would be considered the length 58. The part shown at 84, instead of having one sheave, has five. The means *c* is the same as before, but in the case shown at 84, we have sheaves 90, 91, 92, 93 and 94. In this case the length 57 of the cord 40 is brought over the sheave 42 of the means *c*, thence over the sheave 90, back over the sheave 93, thence over the sheave 91, then over the sheave 94, thence over the sheaves 92 and 43, to where it joins the length 58. The means *d* in this case includes the three sheaves 90, 91, and 92, while the sheaves 93

and 94 are mounted in a yoke and fastened to the retaining means 10 adjacent the means *c*. Cords, as 59 are provided as before and are connected to the yoke portions that go to carry the sheaves 87 and 88, and the sheaves 70 90, 91 and 92. We will designate the sheaves 87 and 88 by the symbol *g*, and the sheaves 90, 91 and 92 by *h*. The sheave 89 will be designated as *j*, and the sheaves 93 and 94 by *k*. Now, the means *g* and *h* of the portion as 75 shown at 83 and 84 have their cords 59 extending so that they may pass to the right as shown in Figure 14, directly over the sheave 95 located as at 96. At 85 we provide mechanism identical with that shown 80 at *h* and *k* and at 86 we provide the mechanism identical with *g* and *j* as shown at 83. However, in the latter case, which we will designate as *g*¹, *j*¹, *h*¹, *k*¹, they are turned so that the cords 59 connected with the same 85 will draw them to the left of the figure as shown. To accomplish this, we provide two sheaves, as 97 and 98, joined to the retaining medium 10 as at 99. The cords 59 pass over said sheaves 97 and 98 and then back so that 90 they may pass over the sheave 95. The sheave 95 may be one sheave or it may be a plurality of sheaves similar to that shown in Figure 13, with the exception that the sheaves 73 would not be necessary. Of course, it is understood that in Figure 14 95 the parts are greatly exaggerated and as a matter of fact some medium for containing the elements as illustrated at *g*, *h*, *j*, *k*, and *g*¹, *h*¹, *j*¹, and *k*¹, might be provided such as 100 shown in Figure 15.

In Figure 15 the retaining medium 10 may be made of box-like formation. This form of retaining medium is designated as *m*. Said medium *m* is provided with a top 105 100, base, 101, and side members, 102 and 103, and end members 104. Within said medium *m* are arranged a series of partitions *n*, in spaced relation to each other. The bottom member 101 may be perforated as at 105 110 to allow the continuous cord member 40 to pass upwardly into the same. The space confined between the interior wall of the side 103 and the partition *m* as at 106 may be arranged to hold the mechanism *c*, *j* and *g* similar to that which would be at a point as 83 in Figure 14. The mechanism shown at 84 of Figure 14 would be contained between the next two partitions, and perforations would be provided in the base 101 so 115 that the continuous cord 40 might pass upward through the same for engagement with the different members *c*, *h* and *k*. It is therefore obvious that all the different members would be confined between partitions and 120 that they would not become entangled with one another. It is also obvious that one cord might be joined to all of the members 59, which cord, as 107, would be joined to an ornamental tassel 108.

Pulling downwardly upon the tassel 108 would cause the curtain to move upwardly and the particular arrangement of the mechanism just described would compensate 5 for the change of the length in the different continuous cords. It has been demonstrated that a curtain four feet in length and two feet wide, by using mechanism as illustrated in Figure 14, may be drawn completely up- 10 wardly by a pull of less than two feet downward upon the tassel 108. It is obvious that any number or changes in the number and relations of the sheaves might be made in relation to the size of the curtain and the 15 number of parallel shirred portions thereof. It must be understood, however, that the particular arrangement of the multiplying tackles or sheaves as illustrated in Fig. 14 would have to correspond. That is to say, 20 the tackles shown at *g* and *h* would have to be similar and contain the same number of sheave elements, otherwise the rod 12 would move zigzag. Obviously the multiplying tackle *g* would move faster than the multiplying tackle *h*. If, however, it were desired to use the tackles *g* and *h* as illustrated 25 in Figure 14, it would be necessary to join the cords 59^a attached to said tackles and then provide a further cord carrying a 30 sheave element such as illustrated in Figure 8, the sheave wheel 54 having the bight of the joined cord lengths moving over the same and connecting the tackles *g* and *h*; and a further cord 59 would connect the 35 tackle *d* and would pass over the sheave 95. This arrangement of course would compensate for the difference in movement between the two multiplying tackles *g* and *h*. In the showing the multiplying tackle *g* would 40 move one-half as far as the curtain was raised, while the multiplying tackle *h* would move one-third as far as the curtain was raised. Consequently the compensating medium above mentioned would be necessary if 45 it were desired to use this arrangement, as the multiplying tackle *g* would soon catch up with the multiplying tackle *h* when they were moved.

It is to be noted in Figure 1 that the cords 50 40, as well as the friction means either *a* or *b*, do not appear all of the braids of said figure. It is customary in mounting the curtains *A* to have the cord members 40 on the outside of said curtain *A* adjacent the 55 window *W* or other medium. This arrangement, of course, gives the curtain a pleasing appearance within the room and as the cords for moving the curtain as well as the friction members *a* or *b*, are small, they will not 60 be observed by people on the outside of the house. As stated, a lambrequin *L* is mounted so as to cover the top of the curtain *A*, and it is beneath this lambrequin that the curtain is folded. Obviously, some form of

lambrequin might be used on the other side 65 of the curtain so that the discontinuous portions, or folded or gathered portions of the curtains may not be seen from the opposite side of the window or other medium. This is a matter of preference and in general 70 practice the lambrequin is only placed on the interior as illustrated. The friction means *a* or *b* may be covered with fabric if desired, or may be enameled. In place of 75 using pulley members it is possible, of course, to use a clutch member similar to the clutch member used for holding tie pins and in place of the other sheave members screw eyes might be used. This is all a matter of 80 preference and depends upon the amount of money to be expended upon a given job.

It is obvious that many changes and variations and modifications may be made in departure from the particular description and showing of the accompanying drawings, in 85 adapting the invention to varying conditions and requirements of use and service, without departing from the true spirit of the invention.

Having thus described my invention, what 90 I claim and desire to secure by Letters Patent is:

1. The combination, with a curtain, adapted to gather at a zone adjacent its line of attachment with a member, of means adapted to maintain said gathering in progressive diminishment adjacent said line of attachment until adjustment of the curtain into position of extension is approximately completed.

2. The combination, with a curtain, of operating means therefor, and means co-acting therewith, whereby the curtain is gathered in one operation thereof in a definite zone adjacent its line of attachment with a member, and which gathered formation is retained adjacent the line of attachment for diminishment during the reverse operation of the curtain.

3. The combination, with a curtain, of operating means for said curtain, and friction elements joined with said curtain and frictionally engaging said means whereby during movement of said means the curtain gathers in a zone at the top of the curtain 115 with the gathering continuously maintained in progressive diminishment at said zone until lowering of the curtain is approximately completed.

4. The combination with a curtain, of a cord secured to the lower end of said curtain for raising the same, members secured to said curtain and frictionally engaging the cord, and means whereby the lower end of said curtain may move downwardly with relation to said cord, the upper end of said cord being held stationary.

5. The combination, with a curtain, of op-

erating cords therefor, and means co-acting therewith, whereby the curtain is gathered in one operation thereof in a definite zone adjacent its line of attachment with a member, and which gathered formation is retained adjacent the line of attachment for diminishment during the reverse operation of the curtain.

6. The combination with: a structure; of 10 a curtain suspended from said structure; an endless cord; means secured to the bottom of said curtain, said cord passing under said means divisioning the cord into a rising length and a lowering length; a series of 15 members secured to said curtain at intervals, said members frictionally engaging said rising length of said cord; means for pulling upwardly on both said rising length and said lowering length of said cord to raise 20 said curtain; and means for holding the upper length of said rising length and releasing said lowering length for the purpose of lowering said curtain.

7. The combination, with a curtain, of 25 means for operating said curtain, and means joined with said curtain and co-operating with said first-named means, whereby during movement of said first-named means the curtain gathers at a determined zone; a 30 member likewise being provided for supporting said curtain at an end thereof, and there being means mounted upon said support over which the means for gathering the curtain passes; said means including a one- 35 way clutch member for preventing movement of the means for operating the curtain in one direction.

8. The combination, with a curtain, of operating means therefor, and friction members 40 co-acting therewith, whereby the curtain is gathered in one operation thereof in a definite zone adjacent its line of attachment with a member, and which gathered formation is retained adjacent the line of attachment for diminishment during the reverse operation of the curtain.

9. A curtain provided at one end with a member for supporting the same, spaced independent continuous cords for gathering 50 said curtain, means adjacent the opposite end of said curtain, through which the continuous cords may pass, means joined with the supporting member over which the continuous cords pass, friction elements 55 spacedly mounted in parallel rows upon said curtain for frictionally engaging separate lengths of the continuous cords, whereby when the cord elements are moved the curtain gathers at a determined zone; said means which is joined to the supporting member over which independent continuous cords pass, including a one-way clutch for preventing movement of each continuous cord in one direction.

10. A curtain provided at one end with a 65 member for supporting the same, spaced independent continuous cords for gathering said curtain, means adjacent the opposite end of said curtain, through which the continuous cords pass, means joined with the supporting member over which the continuous cords pass, friction elements spacedly mounted in parallel rows upon said curtain for frictionally engaging separate lengths of the continuous cords, whereby when the cord elements are moved the curtain gathers at a determined zone, said means which is joined to the supporting member over which independent continuous cords pass, including a one-way clutch for preventing 70 movement of each continuous cord in one direction; there being tackles co-operating with each independent continuous cord for moving said cords.

11. A curtain provided at one end with a 75 member for supporting the same, spaced independent continuous cords for gathering said curtain, means adjacent the opposite end of said curtain, through which the continuous cords pass, means joined with the supporting member over which the continuous cords pass, friction elements spacedly mounted in parallel rows upon said curtain for frictionally engaging separate lengths of the continuous cords, whereby when the cord elements are moved the curtain gathers at a determined zone; said means which is joined to the supporting member over which independent continuous cords pass, including a one-way clutch for preventing 80 movement of each continuous cord in one direction; there being tackles co-operating with each independent continuous cord for moving said cords.

12. An Austrian shade having parallel shirred portions, said shade having a supporting member at one end thereof, and a weighted member transversely mounted at the opposite end thereof, for maintaining the curtain in a taut position, one-way clutch members and sheave members joined to said support member adjacent each parallel shirred portion of said curtain, sheave members mounted upon the weight member, independent continuous cords passing through one each of the sheaves on said weighted member, and having one each of their lengths co-acting with one each of the one-way clutch members and their other lengths passing over one each of the sheave members, and pulley members over which said continuous cords pass for moving said cords; there being friction elements spacedly arranged upon the curtain and extending between the shirred portions, said friction elements combining with the length of each independent 90 95 100 105 110 115 120 125

- continuous cord which co-acts with the one-way clutch, whereby upon moving each of the continuous cord elements the curtain acquires fullness adjacent the supporting member, a releasing of the cord elements permitting the curtain to be re-closed evenly, a certain portion of the fullness being continuously maintained at the top until the curtain is entirely re-closed.
- 10 18. The combination, with a curtain; of means for operating said curtain, and means joined with said curtain and co-operating with said first named means, whereby during movement of said first named means the
- 15 curtain retains fullness in a definite zone, such fullness diminishing automatically and progressively to accommodate the lowering of the curtain.
14. The combination, with a curtain, of operating cords therefor, and friction members co-acting therewith, whereby the curtain is gathered in one operation thereof, in a definite zone adjacent its line of attachment with a member, and which gathered formation is retained adjacent the line of attachment for diminishment during the reverse operation of the curtain; there being multiplying means for moving the curtain at a relatively increased speed.
